United States Patent Office

Des. 191,768
Patented Nov. 14, 1961

191,768

TELEVISION RECEIVER

Rudolph W. Krolopp, Villa Park, and Edwin O. Stastny,
Lombard, Ill., assignors to Motorola, Inc., Chicago,
Ill., a corporation of Illinois

Filed Oct. 14, 1960, Ser. No. 62,497

Term of patent 14 years

(Cl. D56—4)

Fig. 3.

Fig. 4.

The dominant features of the design reside in the portions shown in full lines.

We claim:

The ornamental design for a television receiver, as shown and described.
